UNITED STATES PATENT OFFICE

95,699

DESIGN FOR A SHOE

Leslie A. Morrill, Bradford, Mass.

Application March 14, 1935, Serial No. 55,879

Term of patent 3½ years

To all whom it may concern:

Be it known that I, Leslie A. Morrill, a citizen of the United States, residing at Bradford, in the county of Essex and Commonwealth of Massachusetts, have invented a new, original, and ornamental Design for a Shoe, of which the following is a specification, reference being had to the accompanying drawing, forming a part thereof.

In the accompanying drawing Figure 1 is a view, in perspective, of a shoe showing my new design, the vamp being shown in full lines and the outline of a woman's sandal in dotted lines; and Fig. 2 is a plan view of the vamp only showing the ornamentation in its entirety.

The dominant feature of my design resides in the ornamentation on the vamp comprising laced cut-outs. It will be understood that the particular shape of the vamp is not novel.

As shown in Fig. 1 the vamp is embodied in a woman's sandal but it is contemplated that the vamp may be embodied in oxfords, pumps, one-eyelet and seamless vamp shoes where it will present the same effect as herein illustrated.

I claim:

The ornamental design for a shoe, substantially as shown and described.

LESLIE A. MORRILL.
